[57] CLAIM

The ornamental design for a digital directory, substantially as shown and described.

DESCRIPTION

FIG. 1 is a top isometric view of a digital directory showing my new design;

FIG. 2 is a left side elevational view thereof;

FIG. 3 is a rear elevational view thereof; and

FIG. 4 is a right side elevational view thereof.

The broken lines are shown on the keys in FIG. 1 for illustrative purposes only.
